UNITED STATES PATENT OFFICE

HENRY F. NELSON, OF LA FAYETTE, INDIANA

DESIGN FOR A TOY GUN

Application filed March 14, 1932. Serial No. 43,193. Term of patent 14 years.

To all whom it may concern:

Be it known that I, HENRY F. NELSON, a citizen of the United States, residing at La Fayette, in the county of Tippecanoe and State of Indiana, have invented a new, original, and ornamental Design for Toy Guns, of which the following is a specification.

The invention is illustrated by the accompanying drawing, in which

Fig. 1 is a left hand side elevation of a toy gun showing my invention;

Fig. 2, a top plan view;

Fig. 3, a right hand side elevation; and

Fig. 4, a front elevation with a portion of the handle broken away.

I claim:

The ornamental design for a toy gun as shown.

In testimony whereof I affix my signature.

HENRY F. NELSON.
